UNITED STATES PATENT OFFICE.

EDWARD C. REYNOLDS, OF NEW YORK, N. Y.

SEARCH-LIGHT HOLDER.

1,268,622.

Specification of Letters Patent. Patented June 4, 1918.

Application filed December 4, 1917. Serial No. 205,362.

To all whom it may concern:

Be it known that I, EDWARD C. REYNOLDS, a citizen of the United States, and a resident of the city of New York, borough of Manhattan, in the county and State of New York, have invented a new and Improved Search-Light Holder, of which the following is a full, clear, and exact description.

My invention relates to means for holding a flashlight and more particularly relates to a means for holding a flashlight in operating about an automobile.

An object of my invention is to provide a holding means adapted to be instantly applied to the arm of the user and to readily and detachably receive the flashlight in a manner to permit the latter to be turned through any desired angle relatively to the arm on which the light is supported.

20 A further object of the invention is to provide for reversing the light holding means relatively to the arm engaging means, whereby to nest the same in compact form for convenient carrying in a pocket or in a 25 tool box when the device is not in use.

Reference is to be had to the accompanying drawings forming a part of this specification in which similar reference characters indicate corresponding parts in all the views.

30 Figure 1 is a perspective view of a flashlight holder embodying my invention, showing the same set up for use on the arm of the user;

Fig. 2 is a perspective view of the holder 35 when not applied to the arm of the user and without the flashlight, but with the parts assembled ready for use;

Fig. 3 is a view similar to Fig. 2 but showing the arm-engaging means and the light-holding clamp reversed and nested within the arm-engaging clamp;

Fig. 4 is a transverse vertical section of the holder assembled in Fig. 2.

In carrying out my invention in accordance with the illustrated example, a clamp 10 is provided made from a metal strip to present resilient clamp arms more or less curved and adapted to be sprung onto the arm A of the user. The numeral 11 indicates a corresponding clamp but of smaller size adapted to resiliently hold a flashlight B.

The clamp 11 is secured to a base plate designated generally by the numeral 12 and said plate is provided with a lateral, approximately parallel, resilient arm 13 and spaced from the plate 12 to accommodate the

top of the clamp 10. The clamp 11 is swiveled to the plate 12 so that said clamp is supported in a manner to permit of its being turned through any desired angle to vary 60 the direction of the light rays.

The base plate 12 with its resilient arm 13 detachably receives the clamp 10 and said base is reversible with the clamp 11 to the position shown in Fig. 3 with the clamp 11 65 nested within the clamp 10 so that the assembled device may be carried conveniently in one's pocket or to occupy small space in the tool box.

I would state in conclusion that while the 70 illustrated example constitutes a practical embodiment of my invention, I do not limit myself strictly to the mechanical details herein illustrated, since manifestly the same can be considerably varied without departure 75 from the spirit of the invention as defined in the appended claims.

Having thus described my invention, I claim as new, and desire to secure by Letters Patent:

1. A flashlight holder including a downwardly disposed resilient clamp adapted to be sprung onto the arm of the user, a clamp on top of the first clamp and presenting up-standing resilient arms adapted to detachably receive a flashlight, and means to support the second clamp on the said last mentioned means including a swivel connection for the second clamp permitting the same to be turned laterally relative to the first 90 clamp.

2. A flashlight holder including a clamp presenting arms adapted to be sprung onto the arm of the user, a second clamp adapted to receive a flashlight, a base to which the 95 second clamp is swiveled, a laterally disposed clamp member on said base and forming with the latter a pair of clamp jaws adapted to be slipped laterally onto the first clamp or to be slipped laterally therefrom 100 for connecting or separating the clamps.

3. A flashlight holder including a pair of clamps each presenting curved arms, the one clamp being smaller than the other to nest therein, and means to detachably hold the 105 smaller clamp to the larger clamp in nested relation thereto or imposed on the larger clamp with the clamps back to back.

4. A flashlight holder including a clamp presenting resilient arms adapted to be 110 sprung onto the arm of the user, a separate smaller clamp presenting resilient arms to

receive a flashlight and reversible relatively to the first clamp to nest within said first clamp or be positioned with the clamps oppositely disposed, back to back, and means on one clamp adapted to yieldingly and detachably receive the back of the other of said clamps either with the clamps in nested relation or back to back, said means including a base swiveled to one clamp and a resili-

ent element connected at one side with said base and disposed laterally of the clamp on which it is carried, said base and resilient element being adapted to detachably receive therebetween the back of said other clamp and being engageable and disengageable by a lateral sliding movement to separate or connect the clamps.

EDWARD C. REYNOLDS.
